UNITED STATES PATENT OFFICE

ORRIN HOFFERBERT, OF BEAVER DAM, WISCONSIN, ASSIGNOR TO MALLEABLE IRON RANGE COMPANY, A CORPORATION OF WISCONSIN

RANGE

Application filed April 9, 1931. Serial No. 528,889.

This invention relates to improvements in ranges.

The principal object of the invention is to provide a range having two similar doors in the front, one for the oven and the other to conceal the service drawer, drip pan, and switch controls if the range be electric, or the gas valve handles if the invention is embodied in a gas range, this latter door being hinged 5 preferably at the bottom and arranged to slide into the range structure during the use of the range.

In ranges finished in enamel for instance, it is necessary that the door in being slid to 15 and from position within the range structure be prevented from contact with adjacent portions of the range in order that the finish will not be scratched or otherwise marred. Another object of the invention, therefore, is 20 to provide a guide mechanism for the sliding door which will retain the door in spaced relation with respect to adjacent portions of the range structure while the door is within the structure, or is being moved to, or from, 25 such position.

Another object of the invention is to provide cushioning mechanism for the door to 30 prevent damage thereto in case it should be permitted to fall to horizontal position, such mechanism also being adjustable to re-align the door horizontally should the hinge members become bent during use.

Other objects relate to various features of 35 construction and arrangement of parts which will be apparent from a consideration of the following specification and accompanying drawings wherein:

Fig. 1 is a perspective view of an electric 40 range of the buffet or cabinet type, embodying the present improvements.

Fig. 2 is a broken perspective view illustrating the slidable door moved to the inner 45 position to provide access to electric switches and service drawer.

Fig. 3 is a vertical transverse sectional view through the range showing the slidable door in partially opened position, the dotted lines indicating the horizontal position of the 50 door.

Fig. 4 is a vertical sectional view taken on lines 4-4 of Fig. 3.

Fig. 5 is a detached perspective view of the sliding door and associated guide and adjustable cushioning mechanism.

In the drawings the range is indicated generally by the numeral 10 and in the form shown is of the so-called buffet type having an oven door 11 at the right hand end of the range which may be hinged at the bottom by any approved means. At the other end of the range a door 12 is provided which is similar in appearance to the door 11. The door 12 when closed, as shown in Fig. 1, conceals the switch panel 13, utility drawer 14, and also a drip pan, not shown. The switch controls 15 may be arranged for controlling the current to the hot plates 16, while the control 17 regulates current to the heating elements in the oven. As shown in Fig. 2, 70 the door 12 has been slid into a space or chamber 18 provided in the range structure, thus providing convenient access to the switch controls and the drawer 14. In sliding the door 12 to and from this inner position it is desirable that the door be held out of contact with adjacent portions of the range structure to avoid marring the enamelled surface of the door. To accomplish this result suitable track members 19 are provided in the chamber 18 along which is arranged to slide a guide member 20 which 75 may be formed of sheet metal. Welded or otherwise secured to the vertical ends of the guide member 20 are a pair of forwardly projecting strap or hinge members 21, which have their forward portions preferably offset inwardly from the vertical plane of the rear portions thereof as indicated in Fig. 5. The door 12 has ears 22 welded or otherwise secured thereto, which ears are preferably pivoted, as at 23, to the cooperating hinge members 21. As indicated in Figs. 2, 3 and 5 the door 12 can be lowered to a horizontal position, but further downward movement will be arrested by the contacting of the upwardly turned flange 24 of the lower edge of the door with the members 21. The pivots 23 are positioned nearer to the plane 80 of the front edges of the door than to the 85

flange 24. The door 12 is held in the horizontal position by a pair of coil springs 25 which are secured to the rear edge of the door 12 and to the rear wall of the chamber 18. The door 12 is held in the vertical position by a pair of coil springs 26 which are secured to the front edge of the door 12 and to the front wall of the chamber 18. The door 12 is held in the vertical position by a pair of coil springs 27 which are secured to the rear edge of the door 12 and to the rear wall of the chamber 18. The door 12 is held in the vertical position by a pair of coil springs 28 which are secured to the front edge of the door 12 and to the front wall of the chamber 18. The door 12 is held in the vertical position by a pair of coil springs 29 which are secured to the rear edge of the door 12 and to the rear wall of the chamber 18. The door 12 is held in the vertical position by a pair of coil springs 30 which are secured to the front edge of the door 12 and to the front wall of the chamber 18. The door 12 is held in the vertical position by a pair of coil springs 31 which are secured to the rear edge of the door 12 and to the rear wall of the chamber 18. The door 12 is held in the vertical position by a pair of coil springs 32 which are secured to the front edge of the door 12 and to the front wall of the chamber 18. The door 12 is held in the vertical position by a pair of coil springs 33 which are secured to the rear edge of the door 12 and to the rear wall of the chamber 18. The door 12 is held in the vertical position by a pair of coil springs 34 which are secured to the front edge of the door 12 and to the front wall of the chamber 18. The door 12 is held in the vertical position by a pair of coil springs 35 which are secured to the rear edge of the door 12 and to the rear wall of the chamber 18. The door 12 is held in the vertical position by a pair of coil springs 36 which are secured to the front edge of the door 12 and to the front wall of the chamber 18. The door 12 is held in the vertical position by a pair of coil springs 37 which are secured to the rear edge of the door 12 and to the rear wall of the chamber 18. The door 12 is held in the vertical position by a pair of coil springs 38 which are secured to the front edge of the door 12 and to the front wall of the chamber 18. The door 12 is held in the vertical position by a pair of coil springs 39 which are secured to the rear edge of the door 12 and to the rear wall of the chamber 18. The door 12 is held in the vertical position by a pair of coil springs 40 which are secured to the front edge of the door 12 and to the front wall of the chamber 18. The door 12 is held in the vertical position by a pair of coil springs 41 which are secured to the rear edge of the door 12 and to the rear wall of the chamber 18. The door 12 is held in the vertical position by a pair of coil springs 42 which are secured to the front edge of the door 12 and to the front wall of the chamber 18. The door 12 is held in the vertical position by a pair of coil springs 43 which are secured to the rear edge of the door 12 and to the rear wall of the chamber 18. The door 12 is held in the vertical position by a pair of coil springs 44 which are secured to the front edge of the door 12 and to the front wall of the chamber 18. The door 12 is held in the vertical position by a pair of coil springs 45 which are secured to the rear edge of the door 12 and to the rear wall of the chamber 18. The door 12 is held in the vertical position by a pair of coil springs 46 which are secured to the front edge of the door 12 and to the front wall of the chamber 18. The door 12 is held in the vertical position by a pair of coil springs 47 which are secured to the rear edge of the door 12 and to the rear wall of the chamber 18. The door 12 is held in the vertical position by a pair of coil springs 48 which are secured to the front edge of the door 12 and to the front wall of the chamber 18. The door 12 is held in the vertical position by a pair of coil springs 49 which are secured to the rear edge of the door 12 and to the rear wall of the chamber 18. The door 12 is held in the vertical position by a pair of coil springs 50 which are secured to the front edge of the door 12 and to the front wall of the chamber 18. The door 12 is held in the vertical position by a pair of coil springs 51 which are secured to the rear edge of the door 12 and to the rear wall of the chamber 18. The door 12 is held in the vertical position by a pair of coil springs 52 which are secured to the front edge of the door 12 and to the front wall of the chamber 18. The door 12 is held in the vertical position by a pair of coil springs 53 which are secured to the rear edge of the door 12 and to the rear wall of the chamber 18. The door 12 is held in the vertical position by a pair of coil springs 54 which are secured to the front edge of the door 12 and to the front wall of the chamber 18. The door 12 is held in the vertical position by a pair of coil springs 55 which are secured to the rear edge of the door 12 and to the rear wall of the chamber 18. The door 12 is held in the vertical position by a pair of coil springs 56 which are secured to the front edge of the door 12 and to the front wall of the chamber 18. The door 12 is held in the vertical position by a pair of coil springs 57 which are secured to the rear edge of the door 12 and to the rear wall of the chamber 18. The door 12 is held in the vertical position by a pair of coil springs 58 which are secured to the front edge of the door 12 and to the front wall of the chamber 18. The door 12 is held in the vertical position by a pair of coil springs 59 which are secured to the rear edge of the door 12 and to the rear wall of the chamber 18. The door 12 is held in the vertical position by a pair of coil springs 60 which are secured to the front edge of the door 12 and to the front wall of the chamber 18. The door 12 is held in the vertical position by a pair of coil springs 61 which are secured to the rear edge of the door 12 and to the rear wall of the chamber 18. The door 12 is held in the vertical position by a pair of coil springs 62 which are secured to the front edge of the door 12 and to the front wall of the chamber 18. The door 12 is held in the vertical position by a pair of coil springs 63 which are secured to the rear edge of the door 12 and to the rear wall of the chamber 18. The door 12 is held in the vertical position by a pair of coil springs 64 which are secured to the front edge of the door 12 and to the front wall of the chamber 18. The door 12 is held in the vertical position by a pair of coil springs 65 which are secured to the rear edge of the door 12 and to the rear wall of the chamber 18. The door 12 is held in the vertical position by a pair of coil springs 66 which are secured to the front edge of the door 12 and to the front wall of the chamber 18. The door 12 is held in the vertical position by a pair of coil springs 67 which are secured to the rear edge of the door 12 and to the rear wall of the chamber 18. The door 12 is held in the vertical position by a pair of coil springs 68 which are secured to the front edge of the door 12 and to the front wall of the chamber 18. The door 12 is held in the vertical position by a pair of coil springs 69 which are secured to the rear edge of the door 12 and to the rear wall of the chamber 18. The door 12 is held in the vertical position by a pair of coil springs 70 which are secured to the front edge of the door 12 and to the front wall of the chamber 18. The door 12 is held in the vertical position by a pair of coil springs 71 which are secured to the rear edge of the door 12 and to the rear wall of the chamber 18. The door 12 is held in the vertical position by a pair of coil springs 72 which are secured to the front edge of the door 12 and to the front wall of the chamber 18. The door 12 is held in the vertical position by a pair of coil springs 73 which are secured to the rear edge of the door 12 and to the rear wall of the chamber 18. The door 12 is held in the vertical position by a pair of coil springs 74 which are secured to the front edge of the door 12 and to the front wall of the chamber 18. The door 12 is held in the vertical position by a pair of coil springs 75 which are secured to the rear edge of the door 12 and to the rear wall of the chamber 18. The door 12 is held in the vertical position by a pair of coil springs 76 which are secured to the front edge of the door 12 and to the front wall of the chamber 18. The door 12 is held in the vertical position by a pair of coil springs 77 which are secured to the rear edge of the door 12 and to the rear wall of the chamber 18. The door 12 is held in the vertical position by a pair of coil springs 78 which are secured to the front edge of the door 12 and to the front wall of the chamber 18. The door 12 is held in the vertical position by a pair of coil springs 79 which are secured to the rear edge of the door 12 and to the rear wall of the chamber 18. The door 12 is held in the vertical position by a pair of coil springs 80 which are secured to the front edge of the door 12 and to the front wall of the chamber 18. The door 12 is held in the vertical position by a pair of coil springs 81 which are secured to the rear edge of the door 12 and to the rear wall of the chamber 18. The door 12 is held in the vertical position by a pair of coil springs 82 which are secured to the front edge of the door 12 and to the front wall of the chamber 18. The door 12 is held in the vertical position by a pair of coil springs 83 which are secured to the rear edge of the door 12 and to the rear wall of the chamber 18. The door 12 is held in the vertical position by a pair of coil springs 84 which are secured to the front edge of the door 12 and to the front wall of the chamber 18. The door 12 is held in the vertical position by a pair of coil springs 85 which are secured to the rear edge of the door 12 and to the rear wall of the chamber 18. The door 12 is held in the vertical position by a pair of coil springs 86 which are secured to the front edge of the door 12 and to the front wall of the chamber 18. The door 12 is held in the vertical position by a pair of coil springs 87 which are secured to the rear edge of the door 12 and to the rear wall of the chamber 18. The door 12 is held in the vertical position by a pair of coil springs 88 which are secured to the front edge of the door 12 and to the front wall of the chamber 18. The door 12 is held in the vertical position by a pair of coil springs 89 which are secured to the rear edge of the door 12 and to the rear wall of the chamber 18. The door 12 is held in the vertical position by a pair of coil springs 90 which are secured to the front edge of the door 12 and to the front wall of the chamber 18. The door 12 is held in the vertical position by a pair of coil springs 91 which are secured to the rear edge of the door 12 and to the rear wall of the chamber 18. The door 12 is held in the vertical position by a pair of coil springs 92 which are secured to the front edge of the door 12 and to the front wall of the chamber 18. The door 12 is held in the vertical position by a pair of coil springs 93 which are secured to the rear edge of the door 12 and to the rear wall of the chamber 18. The door 12 is held in the vertical position by a pair of coil springs 94 which are secured to the front edge of the door 12 and to the front wall of the chamber 18. The door 12 is held in the vertical position by a pair of coil springs 95 which are secured to the rear edge of the door 12 and to the rear wall of the chamber 18. The door 12 is held in the vertical position by a pair of coil springs 96 which are secured to the front edge of the door 12 and to the front wall of the chamber 18. The door 12 is held in the vertical position by a pair of coil springs 97 which are secured to the rear edge of the door 12 and to the rear wall of the chamber 18. The door 12 is held in the vertical position by a pair of coil springs 98 which are secured to the front edge of the door 12 and to the front wall of the chamber 18. The door 12 is held in the vertical position by a pair of coil springs 99 which are secured to the rear edge of the door 12 and to the rear wall of the chamber 18. The door 12 is held in the vertical position by a pair of coil springs 100 which are secured to the front edge of the door 12 and to the front wall of the chamber 18.

plane of the bottom of the slide so that when the door is in horizontal position, the slides of the door are spaced above the upper surface of the inner track members, although 5 the central embossed portion 12a of the door may extend below the plane of said tracks.

While the door is in this horizontal position it may be slid with the guide member 20 into the chamber 18 to the position shown 10 in Fig. 2. During this movement the door is retained by gravity in parallel relation with the guide member 20 and is spaced from contact with any adjacent portions of the range structure which might mar its outer 15 enamelled surface.

When it is desired to close the door it is first pulled outwardly in a horizontal direction and then swung upwardly about the pivots 23 to the position shown in Fig. 1. 20 The outward sliding movement of the door is arrested by stops 25 carried by the slide 20 which contact with member 26 secured to the upper forward portion of the chamber 18.

In use the door 12 may frequently be 25 dropped accidentally to horizontal position, or while in extended horizontal position may be used as a support or shelf for heavy pans or other utensils. Such abuse might, of course, cause the enamel to crack or spring 30 the hinge members 21, 22 or bend the flange

24 so the door will not be arrested in horizontal position, in which event it will be 35 likely to have its outer surface marred while being slid into or from the position within the range structure. To avoid the result of such mis-use, I have provided a cushioning mechanism which will absorb the shock of the falling door and thus prevent damage to the hinge members or flange 24. This mech-

40 anism, in the embodiment illustrated, preferably comprises two resilient or spring straps 27 which are welded or otherwise secured at their rear ends 28 to the guide 20. Their forward ends are spaced above the 45 guide, as shown in Fig. 5, and are provided with apertures through which extend bolts having wing nuts 30 on their lower ends. The heads of the bolts are provided with 50 spring confining clips 31 between which and the cushioning members 27 are springs 32.

The free ends of the members 27 project 55 slightly forwardly of the adjacent end of the guide 20 into the path of the flange 24 so that the latter engages the ends of the members 27 before coming into contact with the members 21. In case the door is dropped, the members 27 cushion the latter portion of the swinging movement of the door, that is, the cushioning mechanism begins to function 60 before the door has reached the horizontal position. The stresses and vibrations which would be imparted to the door upon accidentally dropping it were the cushioning mechanism not provided, would be likely to 65 crack the enamel or bend the hinge members

and the lower portion of the door. By adjusting the wing nuts 30, the tension of the springs 32 can be varied as desired. Should the hinge members 21, 22 or the flange 24 become bent through accident or mis-use so 70 the door is not stopped normally in horizontal position, the tension of the springs 32 may be increased sufficiently so the members 27 will hold the door in the proper position.

While I have shown and described one 75 embodiment of the invention for the purpose of illustration, I do not wish to be restricted specifically thereto except as so limited by the appended claims.

What I claim is:

1. A range having a door, a chamber in said range having tracks therein, a guide slideable within said chamber along said tracks, hinge means secured to said door above the lower edge thereof and to said guide whereby said door can be swung into position parallel with said guide, means holding said door out of contact with adjacent portions of the range structure to avoid marring the front surface of said door while the same is being moved into or from said chamber, and means engaging the lower end of said door when the latter is opened to cushion the same as it approaches fully open 90 position.

2. A range having a vertical door, a horizontal door chamber within the range structure, a guide member slideable within said chamber, track members for said guide, hinged members connecting said door adjacent the lower edge thereof to said guide whereby said door can be swung from vertical into horizontal position, said hinged members being arranged to arrest the downward movement of said door, and adjustable means engaging a portion of said door and cooperating with said hinged member for holding the same out of contact with adjacent portions of the range structure during 100 the movement of the door into and from said chamber.

3. A range comprising a structure having a chamber therein, tracks in said chamber, a guide member slideable along said tracks, a door having ears adjacent its lower edge, members carried by said slide and pivotally connected to said ears, said members and ears cooperating to arrest the movement of said door in alignment with said chamber whereby said door can be moved into said chamber and supported therein with the outer surface of said door spaced from adjacent portions of said structure, and resilient means carried by said guide and engaging a portion of said door as it approaches fully open position for cushioning the action thereof.

4. A range having heat regulating members on the front wall thereof, a vertical door adapted to conceal said members when the latter are not in use, a horizontal chamber in 130

said range adjacent the lower edge of said door, a guide slidable within said chamber, hinge members connecting said door adjacent the lower edge thereof to said guide whereby said door can be moved to position in alinement with said chamber, said guide and hinge members normally sustaining said door in such aligned position whereby said door can be slid into said chamber and held out of contact with adjacent portions of said range, and adjustable means carried by said guide and engaging the lower edge of said door for effecting the horizontal alignment of the same with respect to said chamber upon disalignment thereof.

5. The combination with a guide, horizontal tracks upon which said guide is adapted to slide, hinge members projecting forwardly from the forward end of said guide, and a 10 vertical door having ears adjacent the lower end each pivotally secured to one of said members whereby said door can be moved from vertical position to a position parallel with said guide, said pivots being positioned nearer to the outer surface of the adjacent 15 front edges of said door than to the lower plane of said guide whereby when said door is moved to horizontal position the lower edges of said door are disposed slightly above said tracks, said hinge members being adapted 20 to retain said door in said position with respect to said tracks during the movement of said door and guide along said tracks.

6. The combination with a pair of horizontal 25 track members, a guide slidable thereon, a door having ears pivotally secured to said guide, said pivots being positioned nearer to the plane of the forward surface of said door than to the bottom plane of said guide where- 30 by when said door is moved to fully open position the edges of said door will be disposed above and out of contact with said tracks, and cooperating means on said guide and door for restraining the movement of said door beyond said open position.

7. Apparatus of the class described comprising a structure having a vertical door adapted to be swung downwardly to horizontal position, said structure having a horizontal 35 chamber adjacent the lower end of said door, a guide slidable within said chamber, said guide having members for supporting said door and arresting the downward movement thereof at horizontal position whereby said door can be slid into said chamber, and means for cushioning said door as it approaches the horizontal position.

8. Apparatus of the class described comprising a structure having a hinged vertical 40 door adapted to be moved to horizontal position, said structure having a horizontal chamber adjacent the lower end of said door, a guide slidable within said chamber, said guide having members for supporting said door and arresting the downward movement

thereof at horizontal position whereby said door can be slid into said chamber, and means for cushioning said door as it approaches the horizontal position, said means comprising a resilient member carried by said guide and having a portion projecting into the path of the lower portion of said door.

9. A structure having a vertical door, a chamber in said structure adjacent the lower end of said door, a guide slidable within said chamber, hinge members carried by said slide for supporting said door and arresting the downward movement thereof in a position in alinement with said chamber whereby said door can be slid into said chamber, and cushioning means for retarding the downward movement of said door as it approaches said alined position, said means comprising a flexible member secured at one end to said guide, the opposite end of said member projecting into the path of the lower portion of said door for engagement by the latter, and an adjusting device for said member for varying the resistance of the same to the movement of said door after such engagement.

10. A structure having a vertical door, a chamber in said structure adjacent the lower end of said door, a guide slidable within said chamber, hinge members carried by said slide for supporting said door and arresting the downward movement thereof in a position in alinement with said chamber whereby said door can be slid into said chamber, and cushioning means for retarding the downward movement of said door as it approaches said alined position, said means comprising a flexible member secured at one end to said guide, the opposite end of said member projecting into the path of the lower portion of said door for engagement by the latter, and an adjusting device for said member for varying the resistance of the same to the movement of said door after such engagement, said adjusting device comprising a spring on said member, a bolt extending through said spring and member and through said guide, and an adjusting nut on said bolt.

In testimony whereof, I have subscribed my name.

ORRIN HOFFBERT.
